US00D789927S

(12) **United States Design Patent** (10) Patent No.: **US D789,927 S**
(45) Date of Patent: ** *Jun. 20, 2017

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/569,372**

(22) Filed: **Jun. 27, 2016**

Related U.S. Application Data

(63) Continuation of application No. 29/466,582, filed on Sep. 9, 2013, now Pat. No. Des. 760,217.

(57) CLAIM

The ornamental design for an electronic device, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a bottom front perspective view of an electronic device showing the claimed design;

FIG. 2 is a front view thereof;

FIG. 3 is a bottom perspective view thereof;

FIG. 4 is an enlarged bottom front perspective view thereof;

and,

FIG. 5 is an enlarged bottom perspective view thereof.

1 Claim, 5 Drawing Sheets
(5 of 5 Drawing Sheet(s) Filed in Color)

FIG. 1

FIG. 2

FIG. 3

FIG. 4

FIG. 5

UNITED STATES PATENT AND TRADEMARK OFFICE
CERTIFICATE OF CORRECTION

PATENT NO. : D789,927 S
APPLICATION NO. : 29/569372
DATED : June 20, 2017
INVENTOR(S) : Akana et al.

Page 1 of 1

It is certified that error appears in the above-identified patent and that said Letters Patent is hereby corrected as shown below:

Page 3, in Column 1, add the following paragraph below the description of FIG. 5:
The dot-dash lines in the figures show boundaries that form no part of the claimed design.

Signed and Sealed this
Fifth Day of September, 2017

Joseph Matal
